KEY RECEPTACLE

Homer H. De Berry, Tulsa, Okla.

Application March 3, 1937, Serial No. 128,871

7 Claims. (CL 70—456)

The invention relates to key receptacles wherein keys are disposed within a casing and are projected therefrom when desired for use and has for its object to provide a device of this character comprising a casing having a chamber open at its ends and pivotally connected keys within the chamber and controlled by a finger engaging member for projecting either key through the open end of the casing.

10 A further object is to form the openings in the ends of the casing whereby when a key is projected therefrom, the casing may assume an angular position in relation to the key, for instance when the key is in a lock.

15 A further object is to provide the keys with shoulders cooperating with shoulders carried by the casing whereby when a key is drawn into the casing, it will pivotally move into longitudinal relation with the casing. Also to provide shoulders on the keys at opposite sides of the pivotal points of the keys and cooperating with the walls of the casing for maintaining the keys, when within the casing, in alignment and against pivotal movement.

20 25 A further object is to provide the adjacent ends of the keys with overlapped reduced portions having an expansible finger control member within registering apertures thereof and cooperating with recesses in one side of the casing for holding the keys in extended or retracted positions.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

30 40 In the drawing:

Figure 1 is a perspective view of the key holder showing one of the keys extended and in an angular position.

Figure 2 is a longitudinal sectional view 45 through the key receptacle, showing in dotted lines the positions assumed by the key extended.

Figure 3 is a perspective view of the keys removed from the casing.

Figure 4 is a longitudinal transverse sectional view 50 through the receptacle and keys, taken on line 4—4 Figure 5.

Figure 5 is a side elevation of the key receptacle, showing one of the keys extended and before it assumes an angular position.

55 Referring to the drawing, the numeral 1 design-

nates the casing of the key holder, which casing has a chamber 2 extending longitudinally therethrough and terminating in open ends 3, through which either of the keys 4 or 5 is adapted to be extended when it is desired for use. The casing side walls 6 terminate in shoulders 7 spaced from the ends of the casing at opposite sides thereof, and therefore it will be seen that when either key is projected through the open ends 3, it may assume a right angular position as shown in Figures 1 and 2 with the key shoulders 8 engaging the shoulders 7, whereby when the particular key is drawn into the casing, it will pivot from the dotted line position shown in Figure 2 to the full line position shown in said figure. The other shoulders 9 of the keys 4 and 5 are positioned whereby they will engage the inner sides of the casing walls 6 when the keys are within the casing and will maintain the keys in longitudinal alignment with the casing and against pivotal movement while they are housed and while being carried in a pocket, thereby preventing noise and at the same time preventing constant wear on the bearing apertures 10 in the overlapped reduced pivotally connected portions 11 of the 25 keys.

The keys are pivotally connected together by means of telescopically engaged cup shaped members 12 and 13, which are in reverse position and have disposed therein an expansion spring 14, which normally forces the member 13 outwardly so that it can be received in any of the recesses 15 or 16 inside of the casing 1, and on opposite sides of the elongated slot 17, through which the finger engaging member 18 extends. The finger 30 engaging member is threaded into the cup shaped member 13 and when depressed moves out of the recesses 15 or 16, and at which time the operator can longitudinally move the same for projecting either key from the casing.

When the spring actuated member 13 is in the recesses 16, the keys are entirely housed within the casing 1, and it will be noted by referring to Figure 2, all of the shoulders 8 and 9 are engaging the walls 6, and said walls, in combination with the recesses 16 in which the cup shaped member 13 is disposed, will hold the keys against pivotal movement, and the keys will be positively held within the casing.

When it is desired to use a particular key the 50 operator places his finger on the finger engaging member 18 and forces the same inwardly. This action will compress the spring 14 and remove the cup shaped member 13 from the recesses 16; then the operator forces the member 18 towards 55

the end of the casing and until it reaches one of the recesses 15, at which time the operator removes his finger from the member 18 and the key may then be moved to the angular position shown in Figure 1 for use. This particular angular position is desirable where it is not safe to have the casing sticking outwardly, for instance where it is in the ignition lock of an automobile. This angular position also allows 10 the casing to be used as a lever in turning the key, particularly where the lock is hard to work.

The invention having been set forth what is claimed as new and useful is:

1. A key holder and receptacle comprising a 15 casing having a chamber extending entirely through the same, reversely positioned keys within the casing, the adjacent ends of said keys being pivotally connected together and means whereby either key may be projected through one 20 of the open ends of the chamber.

2. A key holder and receptacle comprising a casing having a chamber extending entirely through the same, reversely positioned keys within the casing, the adjacent ends of said keys being 25 pivotally connected together, a yieldable finger engaging member forming the pivotal connection between the keys, said pivotal connection cooperating with a plurality of spaced recesses carried by the casing for holding either key in extended position or in retracted position.

3. A device as set forth in claim 1 including 30 cooperating means carried by the casing and keys whereby when the keys are extended they can assume an angular position in relation to the casing and when retracted within the casing will be held against pivotal movement in relation to each other and to the casing.

4. A key holder and receptacle comprising a 35 casing having a chamber extending entirely through the same and through which keys are projected, axially aligned keys within the cham-

ber, the adjacent ends of said keys being pivotally connected, a finger engaging member extending through one side of the casing and through an elongated slot therein and carried by the pivotal connection between the keys, an expandable member forming said pivotal connection, said expandable member cooperating with recesses adjacent the casing slot for holding either key extended or in retracted positions.

5. A device as set forth in claim 4 wherein the 10 keys, when extended may assume an angular position in relation to the casing and cooperating shoulders carried by the keys and casing whereby when a key is retracted from its angular position, it will be pivotally moved into alignment with 15 the casing chamber and the other key.

6. A device as set forth in claim 4 wherein the 20 expandable connection between the adjacent key ends is formed by telescopically engaged cup shaped members and an expansion spring within 25 said cup shaped members.

7. The combination with a key holder comprising a casing having a chamber extending entirely through the same with its open ends extending around the ends of the casing and inwardly to a point spaced from the ends of the casing, keys slidably mounted within the chamber of the casing and adapted to be projected from the open ends of the chamber, shoulders carried by the keys and cooperating with the 30 shoulders formed by the open ends of the casing for allowing the keys to assume an angular position in relation to the casing when extended and to return the keys to longitudinal position when retracted, overlapped reduced ends carried 35 by the keys and having registering apertures, and an expandable spring actuated member in said apertures and forming a combined pivotal connection between the keys and holding means for keys.

HOMER H. DE BERRY.
